CLAIM

The ornamental design for a combined spray pump dispenser and squeegee for cleaning windshields, as shown and described.

DESCRIPTION

FIG. 1 is a front perspective view of a combined spray pump dispenser and squeegee for cleaning windshields showing my new design;

FIG. 2 is a rear perspective view thereof; and

FIG. 3 is an end elevational view as seen from the bottom of FIG. 2.

The side opposite that shown in FIG. 2 has an appearance identical to the side shown.
